AUTOMATIC TRAIN BRAKE CONTROL

Clyde C. Farmer, Pittsburgh, Pa., assignor to The Westinghouse Air Brake Company, Wilmerding, Pa., a corporation of Pennsylvania

Application June 18, 1937, Serial No. 148,945

32 Claims. (Cl. 303—18)

This invention relates to train control apparatus of the type automatically operative in response to track signals for controlling the air brakes on a railway train, and particularly to automatic train control equipment having means associated therewith for permitting the engineer to retain control of the application of the brakes by acting as required promptly in response to an unfavorable traffic signal.

10 Train control apparatus has heretofore been proposed which is automatically set in operation after a necessarily short interval, usually about six seconds, following communication of an unfavorable traffic signal, to take complete control of the brakes and to effect an application thereof, generally at a full service rate. With such equipment the engineer may, by acting within the allowed interval to effect an application of the brakes by the usual operation of the brake valve, suppress the automatic operation of the train control apparatus, and thus retain control of the brakes. Occasionally, however, the engineer of a train may fail to perform the required act in response to a danger signal in time to suppress an automatic train control application, due to inadvertence or other cause such as, possibly, a faulty operation of the signal responsive timing mechanism included with the train control apparatus.

20 If the engineer thus fails to act in time to suppress the automatic operation of the train control apparatus, the train control apparatus then effects a full service application automatically. When the train control apparatus of the above type is once set in operation as just explained, control of the application of the brakes is thus taken from the engineer, who can thereafter do nothing to regulate the rate at which the application is effected, although he can usually move the brake valve to lap position to prevent complete loss of brake pipe pressure.

25 It is well known, however, that in order to prevent dangerous slack action in a train, the rate and manner of effecting a service application of the brakes should be controlled in accordance with the conditions of service, such as the length of the train and the degree of brake pipe leakage. On a long train, for example, it is desirable first to effect a light application of the brakes in order to cause gentle gathering of the slack between the cars, after which a second stage application of greater degree may be effected with safety. Since a train control equipment is primarily a safety device and is thus adapted to function for applying the brakes only under ex-

ceptional circumstances, it is generally not desirable to provide in addition complicated and expensive mechanism designed to govern the rate of effecting automatic application of the brakes in accordance with varying service conditions. 5 On the other hand, there are obvious advantages to be gained in employing, with a train control apparatus, a manually operated braking equipment of the type designed to permit the desired flexible control of the brakes on trains under 10 various service conditions, such as the well known No. 8 ET air brake equipment, together with means permitting the manually operated equipment to be rendered effective to control the rate at which the brakes are applied even after the 15 train control apparatus has been set in operation.

One object of my invention is to provide an improved train control equipment embodying the above advantages.

20 Another object of my invention is to provide an improved train control equipment having means adapted to respond to operation of a brake valve, after operation of the train control mechanism has begun, to check the automatic reduction in brake pipe pressure for permitting a split 25 or two stage reduction to be effected by the engineer.

25 A further object of my invention is to provide an automatic train brake control equipment having a suppression feature for permitting the engineer to prevent operation of the equipment to effect a train control application of the brakes by performing a required act in response to an 30 adverse signal indication, and having in addition a recapture mechanism adapted to be operated 35 through the medium of the brake valve, immediately after an automatic reduction in brake pipe pressure has been initiated by the train control equipment, to enable the engineer to regain control of the brakes for completing the brake application.

35 A still further object is to provide improved 40 automatic brake control equipment including a recapture mechanism operative to permit manual 45 control of a reduction in brake pipe pressure initiated automatically, which equipment is adapted to be employed with existing standard train brake and signal equipment.

50 Other objects and advantages will appear in the following more detailed description of my invention, taken in connection with the accompanying drawings wherein:

55 Fig. 1 is a diagrammatic sectional view of a

train control equipment embodying my invention;

5 Figs. 2 and 3 are diagrammatic development views showing the port connections established in different positions of the upper and lower rotary valves, respectively, of the brake valve device shown in Fig. 1;

10 Fig. 4 is a diagrammatic sectional view of the application slide valve portion of the train control equipment shown in application position; and

15 Fig. 5 is a fragmentary plan view of the engineer's brake valve device illustrating different positions thereof.

20 Referring to Fig. 1 of the drawings, there is provided an engineer's brake valve device 1, a pipe bracket 2, to which the brake valve device is secured, a brake pipe 3, a casing section 4 secured to the pipe bracket 2 and containing the recapture valve and application valve mechanisms, respectively, another casing section comprising a suppression valve portion 9 and a reduction ensuring valve portion 10, a timing valve device 11, and a magnet valve device 12.

25 As shown in the drawings, the timing valve device 11 and the magnet valve device 12 may be embodied in a unitary structure, and are adapted to cooperate in response to changes in traffic signal indications for initiating operation 30 of the train control apparatus after the lapse of a predetermined interval. The magnet valve device 12 comprises a supply valve 14 mounted in a valve chamber 15 and having a fluted stem 16, a vent valve 17 mounted in a valve chamber 18 and having a fluted stem 19 which operatively engages the stem 16, and a magnet 20, which, when energized, is adapted to maintain the vent valve 17 seated and the supply valve 14 unseated against the pressure of a spring 21 disposed in 35 the chamber 15. The magnet 20 may be energized by current induced from a track signal circuit while traffic conditions are favorable, and is adapted to be deenergized when traffic conditions become unfavorable.

40 45 The valve chamber 15 in the magnet valve device communicates through a passage 23 with the outlet of a feed valve device 24, the inlet of which is connected through a pipe 22 with the usual main reservoir 25, and which may be of any desired type adapted to supply fluid at a predetermined pressure to the chamber from the main reservoir. The valve chamber 18 in the magnet valve device communicates by way of a passage 26 and a whistle device 27 with the atmosphere.

50 55 The timing valve device 11 is adapted to be governed by the magnet valve device 12 and comprises a casing having a valve chamber 29 containing a double beat valve 30 which has a fluted stem 31 extending into a chamber 32 and subject to the pressure of a spring 33 therein, and which valve also has a stem 35 extending downwardly into a chamber 36. The chamber 36 is open to the atmosphere through a passage 37 and has slidably mounted therein a valve piston 38, which is normally urged into an upper seated position by the pressure of fluid in a chamber 39 and in a timing chamber 40 connected thereto. With the valve piston 38 in this position, a spring 42 disposed between the lower wall thereof and the end of the stem 35 is adapted to maintain the double beat valve 30 in its upper seated position for connecting the chamber 29 to atmosphere through chamber 36, as shown in the drawings. 60 65 70 75 A spring 43 is provided for urging the valve pis-

ton 38 downwardly in opposition to the fluid pressure in the chamber 39.

5 The timing valve device 11 is adapted to function to control the operation of an application valve device in effecting an automatic reduction in pressure of fluid in the brake pipe, and as shown in Fig. 1 of the drawings the chamber 32 in the timing valve device is connected by way of a pipe 44 with a piston chamber 45 formed in the casing section 4 and containing an application piston 46 that is adapted to operate an application slide valve 47 through the medium of a stem 48. The application slide valve 47 is mounted within a valve chamber 50 formed in the casing section 4, and is operative when moved from the normal or release position illustrated in Fig. 1 to an application position to initiate an automatic train control application of the brakes in the manner hereinafter described. A spring 51 is interposed between the application piston 46 and the upper wall of the chamber 45 for urging the piston and the application slide valve 47 into the normal position.

10 15 20 25 30 35 40 45 50 55 60 65 70 75 80 85 90 95 100 Also contained in the casing section 4 is a recapture valve mechanism, which, in accordance with my invention, when operated in the manner hereinafter described functions to check the rate at which an automatic application of the brakes is effected after the application has been initiated by operation of the train control apparatus including the application slide valve 47. The recapture valve device comprises a cylindrical valve element 54 slidably mounted in a bore 55 formed in the casing section 4, which valve element has an annular rib 56 adapted for seating engagement with a gasket 57 that is interposed between the casing section 4 and a cover plate 4a and is adapted to control communication between the bore 55 and a passage 58, which is connected to a service reduction reservoir 60. A spring 61 is interposed between the valve element 54 and the cover plate 4a for urging the valve element away from the gasket 57. For operating the valve element 54 there is provided a valve piston 63 having at one side a pressure chamber 64 and at the other side an atmospheric chamber 65 through which extends a stem 66 which is secured to the valve piston 63 and has its upper end in operating engagement with a sealing disc 68 that is disposed in engagement with the lower side of the valve element 54. The sealing disc 68 is adapted to engage an annular rib 69 formed in the casing section 4 at the uppermost end of the chamber 65, when the valve element 54 is in the unseated position illustrated in Fig. 1 of the drawings.

It is a function of the reduction ensuring valve device 10 to prevent a complete suppression of an automatic train control application of the brakes in case the engineer, while acting promptly 5 in response to an unfavorable traffic signal, effects an insufficient reduction in brake pipe pressure. The reduction ensuring valve device 10 may comprise a flexible diaphragm 80 subject to the opposing fluid pressures in a diaphragm chamber 81 and in a diaphragm chamber 82, and adapted to operate a double beat valve 83 which is contained in a valve chamber 84 and is normally urged toward its upper seated position by the pressure of a spring 85 disposed in a chamber 10 15 86, the valve 83 in this position being adapted to maintain communication from the valve chamber 84 through chamber 86 and a restricted exhaust passage 87 to the atmosphere.

The brake valve device 1 comprises a lower 20 casing section 90, an intermediate casing section 91, and an upper casing section 92, the lower casing section having associated therewith an equalizing discharge valve device 93, and the intermediate casing section 91 having formed therein 25 a valve chamber 95 containing an upper rotary valve 96 and a lower rotary valve 97, which are adapted to be operated through the medium of a rotary shaft 99 provided with the usual operating handle 100. As is best shown in Fig. 5 the 30 brake valve device 1 has running, first service, lap, service and emergency positions, it being understood that a full release position might also be provided if desired.

An exhaust valve 102 is disposed in a valve chamber 101 formed in the upper casing section 35 92 of the brake valve device, and is normally urged into seated position by the force of a spring 103. The exhaust valve 102 has a fluted stem 104 operatively mounted in a suitable bore and 40 extending into a chamber 105 which is open to the atmosphere by way of a passage 106. Mounted on the shaft 99 is a cam 108 which is engageable with the end of the stem 104 and is operative 45 to maintain the exhaust valve 102 in unseated position in all positions of the brake valve device except running position, as hereinafter explained.

The equalizing discharge valve device 93 comprises a brake pipe discharge valve 110 adapted to control the discharge communication from a 50 chamber 111 which is connected to the brake pipe 3 by way of a passage 112, said valve being provided with a stem having a collar 114 against which a biasing spring 115 acts for normally urging the valve 110 into seated position. The 55 collar 114 is adapted to be operatively engaged by one arm of a bell crank lever 116 which is pivotally mounted upon a pin 117 carried by the casing, the other arm 118 of the bell crank lever being provided with a rounded end 118a which 60 is operatively disposed in a suitable opening formed in the stem of an equalizing piston 119. The equalizing piston 119 is subject on the lower side to the pressure of fluid in the chamber 111 and on the upper side to the pressure of fluid 65 in a chamber 121, which communicates by way of a passage 122 with the usual equalizing reservoir 123. The arm 118 of the bell crank lever is also adapted to engage the upper end of a 70 stem 124 connected to a maintaining valve 125, which is mounted within a valve chamber 127 and is normally urged to its seat by the force of a spring 128 disposed in the valve chamber.

Associated with the brake valve device 1 is a 75 brake pipe cut off valve device 130, which is operative to cut off the supply of fluid under

pressure by way of the brake valve device to the brake pipe 3 in the event of operation of the application slide valve 47 and other elements of the train control apparatus to effect an automatic reduction in brake pipe pressure. The cut off valve mechanism 130 comprises a valve 131 5 contained in a valve chamber 132 and adapted to be operated through the medium of a stem 133 by a piston 134, which is subject to the opposing pressures of fluid in a chamber 136 and in a chamber 137 that is connected with the chamber 132 through an opening 138 formed in the wall separating said chambers. The valve 131 is adapted to engage an annular seat 139 surrounding the opening 138 for cutting off communication between the valve chamber 132 and the chamber 137, and is normally urged away from the seat by the pressure of a spring 140 15 disposed in the chamber 136 and acting against the piston 134.

In operation, fluid under pressure supplied in the usual manner to the main reservoir 25 flows therefrom by way of the pipe 22 to the feed valve device 24, which is operative in the usual manner to supply fluid at reduced pressure through the 20 passage 23 to the valve chamber 15 in the magnet valve device 12. Assuming that the track signal conditions are favorable so that the magnet 20 is energized for holding the vent valve 17 seated and the supply valve 14 unseated as shown in 25 Fig. 1 of the drawings, fluid under pressure is permitted to flow past the valve 14 and the fluted stem 16, through a passage 150, past a ball check valve 151, and through a passage 152 in the timing valve device 11 to the connected chambers 39 30 and 40. Fluid under pressure in the chamber 39 acts against the valve piston 38 so as to move the valve piston to its upper seated position against the force of the spring 43, thereby causing the double beat valve 30 to be urged to its 35 upper seated position as shown in the drawings, wherein communication from the chamber 32 to the valve chamber 29 is cut off.

Fluid under pressure is also supplied from the main reservoir 25 by way of a pipe and passage 40 154 to the chamber 50 which contains the application slide valve 47, and from the chamber 59 fluid under main reservoir pressure is permitted to flow through a restricted port 155 formed in the application piston 46 to the piston chamber 45 50 and thence by way of pipe 44 to the chamber 32 in the timing valve device 11. As the pressure of fluid on opposite sides of the application piston 46 is thus equalized, the spring 51 is permitted to act through the medium of the 55 piston and the stem 48 to maintain the application slide valve 47 in the release position as shown in Fig. 1 of the drawings.

Fluid under pressure is at the same time supplied from the main reservoir 25 through a pipe 60 157 to a feed valve device 158, which is operative in the usual manner to supply fluid at a reduced pressure through a pipe and passage 159 to the valve chamber 95 in the brake valve device 1. With the brake valve device 1 positioned in running position as shown in Fig. 1 of the drawings, fluid under pressure is supplied from the valve chamber 95 through a port 161 in the upper rotary valve 96 and through a passage and pipe 162 to a recapture reservoir 163, which is provided for a purpose hereinafter explained. Fluid under pressure is at the same time supplied from the valve chamber 95 through a port 165 formed in the lower rotary valve 97 and through a passage 70 75 166 in registration with the port to the seat of 75

the maintaining valve 125 in the equalizing discharge valve mechanism 93.

The port 165 in the rotary valve 97 also registers with a passage 168 through which fluid under pressure is supplied to the chamber 132 in the cut off valve device 130. The passage 168 also leads to the seat of the application slide valve 47, and with the application slide valve in the normal or release position illustrated in Fig. 1 of the drawings, a cavity 170 formed in the slide valve connects the passage 168 with a passage 171, so that fluid under pressure is supplied from the rotary valve chamber 95 in the brake valve device by way of the communications just described to the chamber 136 on the left-hand side of the piston 134 in the cut off valve mechanism 130.

With the cut off valve 131 thus maintained unseated by the force of the spring 140 and of the fluid under pressure in the chamber 136 acting on the piston 134, fluid under pressure is supplied from the chamber 132 through the opening 138 and the chamber 137 to the brake pipe passage 112, and thence flows to the chamber 111 in the equalizing discharge valve mechanism 93, and to the brake pipe 3 through which the fluid under pressure is supplied to the brake controlling valve devices, not shown, on cars in the train.

30 A branch 112a of the brake pipe passage 112 leads to the diaphragm chamber 82 beneath the diaphragm 80 of the reduction ensuring valve device 10, and the pressure of the fluid thus supplied to the diaphragm chamber with the aid of the spring 85 acts to maintain the double beat valve 83 in its upper seated position as shown in Fig. 1, in which position communication between the chamber 82 and the valve chamber 84 is cut off while the chamber 84 is connected to the atmosphere by way of the chamber 86 and restricted exhaust passage 87.

At the same time, with the brake valve device 1 in the running position as shown in Fig. 1 of the drawings, a port 178 in the rotary valve 97 registers with a passage 179, so that fluid under pressure is supplied from the chamber 95 through said passage to a cavity 180 in the application supply valve 47 registering therewith, and thence flows through the passage 122 to the equalizing reservoir 123 and the equalizing piston chamber 121. It will be understood that fluid at the pressure carried in the brake pipe 3 is now acting on both sides of the equalizing piston 119, which is thus permitted to rest in its normal position as shown in Fig. 1, while the spring 115 holds the discharge valve 110 seated.

Fluid under pressure supplied from the valve chamber 95 of the brake valve device 1 to the passage 168 as already explained also flows therefrom by way of a branch passage 168a, a cavity 182 in the upper rotary valve 96 and thence through a passage 183 to the diaphragm chamber 81 and a suppression reservoir 184 connected thereto, it being understood that the pressure of fluid thus supplied to the diaphragm chamber 81 is no greater than that of the fluid in the chamber 82 beneath the diaphragm 80, so that the spring 85 will continue to hold the double beat valve 83 in the position shown in Fig. 1.

70 At this time it should be noted that the diaphragm chamber 72 above the diaphragm 71 in the suppression valve device 9 is connected to the valve chamber 84 in the reduction ensuring device by way of a passage 175 having a restrict-

ed portion 176, and also communicates by way of a passage 186 with a cavity 187 in the upper rotary valve 96 in the brake valve device which registers with an atmospheric exhaust port 188. It will further be noted that the diaphragm 5 chamber 73 beneath the diaphragm 71 is likewise connected to the atmosphere through a restricted port 190, a passage 191, a branched passage 192 in the application slide valve 47, and an atmospheric exhaust passage 193, it being 10 assumed that, of course, the application slide valve is in the release position shown in Fig. 1. Since the diaphragm chambers 72 and 73 on opposite sides of the diaphragm 71 in the suppression valve device are thus vented to the atmosphere, the spring 77 is permitted to maintain the double beat valve 74 in its upper seated position as shown in Fig. 1, so that the valve chamber 75 in the suppression valve device 9 is open 15 by way of a chamber 194 and a passage and pipe 20 195 to the double beat valve chamber 29 in the timing valve device 11.

It should be further noted that, with the brake valve device 1 in running position and the application slide valve 47 in release position as shown in Fig. 1 of the drawings, the chamber 64 beneath the recapture piston 63 is connected with the atmosphere by way of a passage 198, the cavity 187 in the upper rotary valve and the exhaust port 188, so that the recapture valve 30 element 54 is maintained unseated by the spring 61. The service reduction reservoir 60 is thus maintained in communication with the bore 55 and thence through a passage 200, the passage 192 in the application slide valve 47, and the 350 passage 193 with the atmosphere. A restricted portion 192a of the passage 192 at this time registers with a passage 202 which is connected by way of a pipe 202 with a reduction limiting reservoir 203, and which passage also communicates through a cavity 205 in the lower rotary valve 97 of the brake valve device with an atmospheric exhaust port 206.

Assuming that the fluid pressure brake system has been charged in the manner just described and that the train is proceeding along the track, if the traffic signal conditions now become unfavorable, so that the magnet 20 in the magnet valve device 12 is deenergized, the spring 21 becomes effective to move the valve 14 into seated position while unseating the valve 17, whereupon fluid under pressure begins to flow from the connected chambers 39 and 40 in the timing valve device 11 by way of the passage 152, through a restricted passage 210, and thence by way of the passage 150, past the valve 17, through the passage 26 and the whistle device 27 to the atmosphere. After a predetermined reduction in the pressure of fluid in the chamber 39, the spring 43 is enabled to shift the valve piston 38 downwardly, thereby permitting the spring 33 to act through the medium of the stem 31 to move the double beat valve 30 into its lower seated position.

With the double beat valve 30 in its lower seated position communication is established between the chamber 32 and the valve chamber 29, and assuming that the engineer has failed to act at this time, fluid under pressure begins to flow from the piston chamber 45 above the application valve piston 46 through the pipe 44, chamber 32, past the valve 30, through chamber 29, pipe and passage 195, chamber 194, past the double beat valve 74 to the valve chamber 75 of the suppression valve device, and thence through 75

- a passage 211 to a stop reservoir 212. Fluid under pressure is thus vented from the piston chamber 45 at a faster rate than that of flow thereto of fluid from chamber 50 through the restricted passage 155 in the piston, and when the pressure in the chamber 45 has been reduced sufficiently below that in the valve chamber 50, the piston 46 and application slide valve 47 are shifted upwardly into application position.
- With the application slide valve 47 in application position, as is shown in Fig. 4 of the drawings, the passage 171 is connected to the exhaust passage 192 in the slide valve, so that fluid under pressure is vented from the chamber 136 in the brake pipe cut off valve device 130, the fluid under pressure flowing from the chamber through the passage 171, passage 192 and passage 193 to the atmosphere. Upon the reduction in the pressure of fluid in the chamber 136 the fluid pressure in the chamber 137 at the opposite side of the piston 134 causes the piston to move the valve 131 against the seat 139, thereby preventing further supply of fluid under pressure to the brake pipe.
- When the application slide valve 47 is moved to application position, a passage 214 formed therein, which has a restricted portion 214a, establishes communication between the passage 122 and passages 200 and 202, with the result that fluid under pressure is permitted to flow from the equalizing reservoir 123 and the equalizing piston chamber 121 through the passage 122, slide valve passage 214, and thence through passages 200 and 202 to the service reduction reservoir 60 and reduction limiting reservoir 203, respectively.
- It will be understood, of course, that the passage 200 at this time communicates by way of the bore 55 and the passage 58 with the service reduction reservoir 60, since the valve element 56 is in the unseated position shown in Fig. 1 of the drawings.
- As the pressure of fluid in the equalizing piston chamber 121 is reduced by flow into the reservoirs 60 and 203 as just described, the fluid pressure in the chamber 111 forces the equalizing piston 119 upwardly, thereby causing the piston to operate the bell crank lever 116 to unseat the brake pipe discharge valve 110. With the discharge valve 110 unseated, fluid under pressure is vented from the brake pipe 3 by way of passage 112, the chamber 111, past the discharge valve 110, through a passage 216 having a restricted portion 217, and thence through the application slide valve passage 192 and the atmospheric exhaust passage 193. As already explained, the fluid pressure in the equalizing piston chamber 121 is at this time permitted to equalize with the initially atmospheric pressure in both the service reduction reservoir 60 and the reduction limiting reservoir 203, the combined capacities of which are such that the consequent reduction in fluid pressure in the chamber 121 causes operation of the equalizing discharge valve mechanism 93 to vent fluid under pressure from the brake pipe at a service rate. When the pressure of fluid in the brake pipe 3 has been thus reduced by automatic operation of the train control apparatus as just described, the usual brake controlling valve devices throughout the train are operated in the well known manner to effect a service application of the brakes.
- While the application slide valve device 47 is in application position as illustrated in Fig. 4 of the drawings for effecting the automatic service application of the brakes in the manner just described, fluid under pressure is supplied from the valve chamber 50 by way of the passage 191 and past a ball check valve 220 to the diaphragm chamber 73 in the suppression valve device 9, thereby insuring against movement of the double beat valve 74 out of the position shown in Fig. 1. It will also be noted that with the application slide valve 47 in application position, the piston chamber 45 is connected by way of a passage 221, a cavity 223 in the slide valve, and a passage 224 with the atmospheric exhaust cavity 187 in the upper rotary valve 96 in the brake valve device which is still in running position as shown in Fig. 1. The stop reservoir 212 is likewise connected to the atmosphere by way of the passage 211, past a ball check valve 225, and through the passage 224.
- It will thus be seen that if the brake valve device remains in running position, the application piston chamber 45 is vented to atmosphere and the application slide valve 42 is consequently held in its application position, thereby permitting continued flow of fluid under pressure from the equalizing piston chamber 121 to the atmosphere, after equalization into reduction reservoirs 60 and 203, by way of the communications hereinbefore pointed out including the passage 202, the cavity 205 in the rotary valve 97, and the exhaust port 206. This would result in the brake pipe pressure being reduced to atmospheric pressure, which is unnecessary in effecting a service application of the brakes.
- In order to prevent complete discharge of fluid under pressure from the brake pipe, the brake valve device 1 should be operated to lap position shortly after operation of the train control apparatus has been begun. With the brake valve device 1 in lap position, the passage 202 communicating with the reduction limiting reservoir 203 is lapped, while the atmospheric communication from the passage 224 communicating with the stop reservoir 212 is similarly cut off, so that after the pressures of fluid in the application piston chamber 45 and in the stop reservoir 212 have equalized, further flow of fluid from said piston chamber is prevented. Continued flow of fluid under pressure from the valve chamber 50 through the restricted port 155 in the application piston 46 then causes the fluid pressure in the piston chamber 45 to increase until the spring 51 is again enabled to move the application piston and the slide valve 47 to the release position as illustrated in Fig. 1 of the drawings.
- When the brake valve handle 100 is moved to lap position the cam 103 carried on the rotary shaft 99 is operated to move the stem 104 and the exhaust valve 102 toward the right-hand, thereby unseating the exhaust valve to permit continued discharge of fluid under pressure from the brake pipe by way of the discharge valve passage 216, a branch 216a of the said passage, and through the valve chamber 101 and the atmospheric exhaust passage 106. When the pressure of fluid in the brake pipe and in the connected chamber 111 has been reduced slightly below the pressure of fluid in the equalizing piston chamber 121 the equalizing piston 119 is operated to effect movement of the discharge valve 110 to seated position, preventing further reduction in brake pipe pressure.
- As shown in Fig. 2, with the brake valve device in lap position the passage 162 leading from the recapture reservoir 163, together with the passage 75

198 leading from the chamber 64 are connected to the atmospheric exhaust port 188 by way of a cavity 226 in the rotary valve 96.

From the foregoing it will be understood that 5 if the brake valve device is allowed to remain in running position or is moved by the engineer to lap position following communication of an unfavorable traffic signal, the automatic train control apparatus becomes operative to effect a full 10 service application of the brakes.

If the engineer desires to prevent a train control application of the brakes, however, then at 15 the time the signal indications become unfavorable, as made known by operation of the whistle 27 in the manner hereinbefore described, the engineer must move the brake valve handle 100 to an application position before the chamber 39 in the timing valve device 11 has been sufficiently reduced to permit operation of the double 20 beat valve 30. Upon movement of the brake valve device to the first service position illustrated diagrammatically in Figs. 2 and 3, fluid under pressure is supplied from the recapture reservoir 163 by way of the pipe and passage 162, 25 through a cavity 227 in the rotary valve 96, and thence by way of the passage 198 to the chamber 64 below the recapture piston 63, and by way of the passage 186 to the diaphragm chamber 72 of the suppression valve device 9. Fluid under 30 pressure thus supplied to the piston chamber 64 operates the recapture piston 63 to shift the valve element 56 upwardly into seating engagement with the gasket 57 against the pressure of the spring 61, thereby cutting off communication between the bore 55 and the service reduction reservoir 60, this operation of the recapture device being, however, of substantially no consequence at 35 this time. Similarly, fluid under pressure supplied to the diaphragm chamber 72 acts against the diaphragm 71 to move the double beat valve 74 into its lower seated position, thereby cutting off communication between the chamber 194 and the valve chamber 75. The suppression valve device 9 is thus operated to prevent any flow of 40 fluid under pressure from the application piston chamber 45 to the stop reservoir 212, which would otherwise occur upon subsequent operation of the timing valve device 11. The application slide valve 47 consequently remains in the release position illustrated in Fig. 1.

Meanwhile, with the lower rotary valve 97 of the brake valve device in first service position, a restricted port 228 formed therein establishes communication between the passages 179 and 55 202 which is also connected through a restricted passage 228a with the atmosphere, with the result that fluid under pressure is vented at a slow rate from the equalizing piston chamber 121 and reservoir 123 by way of the passage 122, cavity 180 in the application slide valve 47, passage 179, cavity 228 and passage and pipe 202 to the reduction 60 limiting reservoir 203, and also by way of said passage 202 and through the restricted portion 192a of slide valve passage 192 and passage 65 193 to the atmosphere. The capacity of reduction limiting reservoir 203 is such that, upon equalization of fluid pressure therein with that in the equalizing reservoir 123, the consequent reduction of pressure in the equalizing piston chamber 121 causes operation of the equalizing discharge valve device 93 to vent fluid under pressure from the brake pipe 3 in an amount sufficient to effect a light application of the brakes for gathering the slack in the train.

70 75 It will be noted that with the brake valve de-

vice in first service position, fluid under pressure is supplied from the rotary valve chamber 95 through a cavity 229 in the rotary valve 97 and the passage 166 to the valve chamber 127, which contains the maintaining valve 125. Thus 5 in case the effect of brake pipe leakage in the train is such as to cause reduction of the pressure of fluid in the chamber 111 at a greater rate than that of reduction of pressure in the equalizing piston chamber 121, the equalizing piston 119 is 10 temporarily moved to its lowermost position in which the arm 118 of the bell crank lever 116 unseats the maintaining valve 125 to permit the supply of fluid under pressure from the valve chamber 127 through the chamber 111 to the 15 brake pipe so as substantially to nullify the undesired effect of the brake pipe leakage. In this way there is avoided the possibility that brake pipe leakage might so augment the intended limited amount of reduction in pressure in the brake 20 pipe as to effect a heavy application of the brakes on forward cars prior to gathering of the slack in the train.

It will be noted that fluid under pressure supplied from the recapture reservoir 163 to the 25 diaphragm chamber 72 in the suppression valve device 9 as hereinbefore described is slowly vented to the atmosphere by way of the passage 175, restricted portion 176, valve chamber 84 and past the double beat valve 83 to the chamber 86 in the 30 reduction insuring valve device, and thence through the restricted passage 87. It will thus be seen that if the engineer permits the brake valve device 1 to remain in first service position until the pressure of fluid in the diaphragm 35 chamber 72 has reduced sufficiently to permit the spring 77 to return the double beat valve 74 to its upper seated position, fluid under pressure will be discharged from the application piston chamber 45 past said double beat valve to the stop 40 reservoir 212 in the manner hereinbefore explained to cause operation of the train control apparatus for effecting an automatic application of the brakes.

It is to be expected, however, that in the ordinary course of handling the train, the engineer will move the brake valve device 1 from the first service position to service position in time to continue operation of the suppression valve device 9 to suppress a train control application of the 50 brakes. When the handle 100 of the brake valve device 1 is moved from the first service position to service position a cavity in the rotary valve 97 having a restricted portion 235 is brought into registration with the passages 179 and 206, 55 as best shown in Fig. 3 of the drawings, and fluid under pressure is then permitted to vent at a service rate from the equalizing reservoir 203 and piston chamber 121 by way of the passage 122, cavity 180 in the application slide valve 47, passage 179, cavity 235 and atmospheric exhaust 60 passage 206. The passage 202 leading from the reduction limiting reservoir 203 is likewise connected to the atmosphere through a passage 236 in the rotary valve 97 and the exhaust port 206. 65 Upon the further reduction in fluid pressure in the equalizing piston chamber 121 thus effected the fluid at brake pipe pressure in the chamber 111 again moves the equalizing piston 119 upwardly, thereby operating the bell crank lever 116 to unseat the brake pipe discharge valve 110, so that fluid under pressure is vented from the chamber 111 and consequently from the brake pipe into the discharge passage 216.

As shown in Fig. 2 of the drawings, with the 75

upper rotary valve 96 of the brake valve device in service position, a cavity 237 in the rotary valve connects passages 230 and 232, while a cavity 239 connects the passage 168a with the passage 186, it being also noted that the passage 198 leading from the recapture piston chamber 64 is vented through a cavity 238 and the atmospheric exhaust port 188. Thus while fluid under pressure vented past the brake pipe discharge valve 110 through the discharge passage 216 may flow at a restricted rate through the restricted passage 217, the branch passage 216a, and past the exhaust valve 102 to the atmosphere, a portion of said fluid under pressure is diverted 10 through the passage 230, cavity 237, passage 232, and past a ball check valve 240 into a valve chamber 241, and thence by way of a restricted passage 242 and a passage 243 to a timing reservoir 244, which is thus charged with fluid under pressure. A spill-over check valve 246, which is normally seated by a spring 247, is provided as a means for limiting the build-up in pressure in the timing reservoir 244, fluid under excessive pressure in passage 243 being permitted to escape 20 therefrom through a branch passage 248 and past the check valve to the passage 232.

It will be observed that the passage 243 leads from the timing reservoir 244 to the chamber 86 within the reduction ensuring valve device 10, 30 from which chamber the fluid may flow past double beat valve 83 and through passage 175 to the diaphragm chamber 72, and also at a slow rate through the restricted atmospheric passage 87. At the same time, fluid under pressure is supplied 35 from the brake pipe 3 through the passage 112, the connected chambers 137 and 132 in the cut off valve device 130, which is still in unseated position, and thence through the passage 168, the passage 168a, the cavity 239 in the rotary valve, 40 and the passage 186 to the diaphragm chamber 72 above the diaphragm 71 of the suppression valve device 9. The diaphragm 71 is thus urged downwardly and double beat valve 74 of the suppression valve device is thereby held in its lower 45 seated position for preventing operation of the train control apparatus as hereinbefore explained, said valve being maintained in this position for a predetermined period of time, due to the effect of fluid pressure remaining in the timing reservoir 244.

The function of the timing reservoir 244 in causing suppression of a train control application of the brakes for a predetermined interval, as above explained, will enable the engineer to 55 employ an alternative method of effecting a two-stage reduction in brake pipe pressure, if preferred, which method is well known and consists in operating the brake valve device to service position initially, then to lap position for an interval, and again to service position. It will be apparent that if this method is used, operation of the train control apparatus will be suppressed during the time required for manually effecting 60 service application of the brakes.

65 When the pressure of fluid in the equalizing reservoir 123 and the piston chamber 121 has been reduced sufficiently to effect a service application of the brakes, the brake valve device may be moved to lap position, in which the cavity 231 in the upper rotary valve 96 maintains communication between the passages 230 and 232, so that fluid under pressure still being discharged from the brake pipe by the equalizing discharge valve device will flow through the same communications to the suppression valve device 9 as were

pointed out in connection with the description of operation in the service position of the brake valve device. When the pressure of fluid in the brake pipe and in the connected chamber 111 has been reduced sufficiently, the equalizing piston 119 is returned to its normal position as shown in Fig. 1 of the drawings, while the spring 115 is permitted to seat the discharge valve 110. The service reduction in brake pipe pressure thus effected results in a service application of the 10 brakes in the usual manner.

Upon the service reduction in brake pipe pressure the pressure of fluid in the diaphragm chamber 82 of the reduction ensuring valve device 10, which is connected with the brake pipe 3 by way of passages 112 and 112a, is correspondingly reduced, and as a result the fluid pressure in the diaphragm chamber 81 and in the suppression reservoir 184 connected therewith becomes effective to operate the diaphragm 80 for moving 20 the double beat valve 83 to its lower seated position, thereby cutting off the atmospheric communication from the valve chamber 84 and connecting said chamber with the diaphragm chamber 82. Fluid under pressure is then supplied 25 from the chamber 82 past the double beat valve 83 and through the chamber 84 and passage 175 to the diaphragm chamber 72 in the suppression valve device, thus permanently suppressing operation of the train control apparatus. 30

When it is desired to effect a release of the brakes, after traffic signal conditions have again become favorable so that the magnet valve device 12 and the timing valve device 11 are again operated to effect movement of the double beat valve 35 30 to its upper seated position, the handle 103 of the brake valve device 1 is returned to running position. With the brake valve device in running position the brake pipe 3 is again charged 40 with fluid under pressure in the manner hereinbefore described, and the brake controlling valve devices on cars of the train are thereby operated in the usual manner to effect the release of the brakes.

From the foregoing it will be apparent that the 45 engineer can suppress an automatic train control application of the brakes by moving the handle of the brake valve device 1 to first service position promptly in response to an adverse signal indication and before operation of the timing valve device 11 to vent fluid under pressure from the application piston chamber 45. Let it now be assumed that the engineer does not act quickly enough to suppress operation of the train control apparatus, and that as a result the application piston 46 has automatically operated to shift the application slide valve 47 into the application position as shown in Fig. 4 of the drawings. With the train control equipment constructed according to my invention, the engineer may recapture control of the application of the brakes, 55 even after automatic operation of the equipment has been initiated by movement of the application slide valve to the application position, by quickly operating the brake valve device 1 to first 60 service position.

If the engineer moves the brake valve handle 100 to first service position immediately after 65 automatic operation of the application slide valve 47, the brake valve device is thereby operated to 70 effect a limited initial reduction in brake pipe pressure in the manner already described, and at the same time effects supply of fluid under pressure from the recapture reservoir 163 by way of the pipe and passage 162, the cavity 227 in 75

the upper rotary valve 196, and passage 198 to the piston chamber 64 below the recapture piston 63. The pressure of fluid thus supplied to the piston chamber 64 moves the piston 63, the stem 66, and the valve element 54 upwardly against the force of the spring 61, until the seat rib 56 of the valve element engages the gasket 57.

With the recapture valve element 54 thus seated, communication from the bore 55 to the passage 58 and the service reduction reservoir 60 is cut off, with the result that, although the application slide valve 47 is in the application position shown in Fig. 4 and communication is established from the equalizing reservoir 123 and piston chamber 121 by way of the passage 122 and through the application slide valve passage 214 to the passages 200 and 202, fluid under pressure from the equalizing reservoir can flow only through the passage 202 to the reduction limiting reservoir 203 and through restricted port 228a to atmosphere. As hereinbefore explained, equalization of the pressure in the equalizing reservoir 123 with that in the reduction limiting reservoir 203 results in operation of the brake pipe discharge valve device 93 to vent a limited amount of fluid under pressure from the brake pipe 3 for effecting a light, slack-gathering application of the brakes.

It will be noted that, with the brake valve device 1 in first service position and the application slide valve 47 in application position, the lower rotary valve 97 will not be effective to vent fluid under pressure from the equalizing reservoir by way of the usual communications including the passage 179, since the passage 179 is lapped at the application slide valve.

Fluid under pressure supplied from the recapture reservoir 163 by way of the passage 186 to the diaphragm chamber 72 in the suppression valve device 9, as hereinbefore explained, acts against the diaphragm 71 to move the double beat valve 74 downwardly so that communication from the chamber 194 to the valve chamber 75 and the stop reservoir 212 is cut off. At the same time, however, the application slide valve cavity 223 connects the passage 221 with passage 224, and fluid under pressure is thus permitted to flow from the application piston chamber 45 to the passage 224 and thence to the atmosphere by way of a cavity 249 in the rotary valve 96 which connects the passage 224 with the atmospheric exhaust port 188 in first service position in the brake valve device. The pressure of fluid in the slide valve chamber 50 is accordingly effective to maintain the application piston 46 in the application position.

Since as hereinbefore explained the diaphragm chamber 72 in the suppression valve device 9 is open to atmosphere by way of the passage 175, valve chamber 74 in the reduction ensuring valve device 10, chamber 86, and restricted port 87, the recapture piston chamber 64 is likewise connected with the atmosphere, when the brake valve device is in first service position, by way of the passage 198, rotary valve cavity 227, and passage 186 leading to the diaphragm chamber 72, and it will be apparent that the fluid pressure in recapture piston chamber 64 and in the recapture reservoir 163 connected thereto will after a predetermined interval reduce sufficiently to permit the spring 61 to move the valve element 54 and the piston 63 downwardly, thereby establishing communication from the bore 55 to the passage 58. With the application slide valve 47 still in application position as shown in Fig. 4 of the drawings, fluid un-

der pressure from the equalizing piston 123 and piston chamber 121 is then free to flow into the service reduction reservoir 60 for completing a full service application of the brakes in the manner already explained.

It will thus be seen that an automatic train brake control equipment constructed in accordance with my invention is adapted to permit the engineer to retain control of the brakes by operating the brake valve in response to an adverse traffic signal to suppress automatic operation of the train control apparatus to effect an application of the brakes before such automatic operation has begun, and that in addition the train brake control equipment is further adapted to permit an engineer, who acts too late to suppress automatic operation of the train control apparatus, to recapture at least some degree of control of the application of the brakes even after the train control apparatus has been set in operation, by operating the brake valve to effect a two-stage reduction in brake pipe pressure.

While one illustrative embodiment of my invention has been described in detail, it is not my intention to limit its scope to that embodiment or otherwise than by the terms of the appended claims.

Having now described my invention, what I claim as new and desire to secure by Letters Patent, is:

1. In a fluid pressure brake, in combination, a brake pipe, a reduction in pressure in which is adapted to effect an application of the brakes, train control mechanism automatically operative in response to signal indications to effect a predetermined reduction in brake pipe pressure, means preventing suppression of the operation of said mechanism after a reduction in brake pipe pressure has been initiated thereby, manually operable means for also effecting reductions in brake pipe pressure, and a recapture means responsive to operation of said manually operable means after a reduction in brake pipe pressure has been initiated by automatic operation of the train control mechanism for limiting the degree of reduction in brake pipe pressure effected by said train control mechanism.

2. In a fluid pressure brake, in combination, a brake pipe, an equalizing reservoir, discharge valve means operative on a reduction in the pressure of fluid in said equalizing reservoir to vent fluid under pressure from said brake pipe to effect an application of the brakes, train control mechanism automatically operative in response to signal indications to effect a reduction in pressure in said reservoir at a certain rate, manually operable means for effecting a reduction in equalizing reservoir pressure at a different rate, and recapture means responsive to operation of said manually operable means after a reduction in equalizing reservoir pressure has been initiated by automatic operation of said train control mechanism for effecting continued reduction in said pressure at said different rate.

3. In a fluid pressure brake, in combination, a brake pipe, a reduction in pressure in which effects an application of the brake, train control mechanism automatically operative in response to signal indications to an application position for effecting a reduction in brake pipe pressure of a certain degree, means rendered effective on operation of said train control mechanism to hold said mechanism in application position, brake valve means operable manually to control the application of the brakes, and recapture

means adapted to operate independently in response to operation of said brake valve means, following automatic operation of the train control mechanism to said application position, for 5 limiting the reduction in brake pipe pressure effected by said train control mechanism to a different degree.

4. In a fluid pressure brake, in combination, a brake pipe, an equalizing reservoir, discharge 10 valve means operative on a reduction in the pressure of fluid in said equalizing reservoir to vent fluid under pressure from said brake pipe, a first reduction reservoir, a second reduction reservoir, train control mechanism automatically operative 15 in response to an unfavorable traffic signal to establish communication from said equalizing reservoir to both of said reduction reservoirs, recapture means operative to cut off communication from said equalizing reservoir to one of said reduction reservoirs, and manually operative 20 means for controlling operation of said recapture means.

5. In a fluid pressure brake, in combination, a brake pipe, an equalizing reservoir, a discharge 25 valve operative on a reduction on the pressure of fluid in said equalizing reservoir to vent fluid under pressure from said brake pipe, a first reduction reservoir, a second reduction reservoir, train control mechanism automatically operative 30 in response to an unfavorable traffic signal to establish communication from said equalizing reservoir to both of said reduction reservoirs, recapture means operative upon an increase in fluid pressure in a chamber to cut off communication 35 from said equalizing reservoir to one of said reduction reservoirs for varying the rate of application of the brakes effected by the train control mechanism, and manually operable means adapted to supply fluid under pressure to 40 said chamber.

6. In a train control brake apparatus, in combination, a brake valve device normally adapted for operation to effect an application of the brakes of any desired degree, control mechanism 45 automatically operative in response to adverse traffic signal conditions to effect a predetermined degree of application of the brakes and to prevent normal operation of said brake valve device, and recapture means adapted to function independently of said control mechanism and operative 50 in response to movement of said brake valve device to an application position, during initial operation of said control mechanism in effecting an application of the brakes, for causing said 55 control mechanism to effect subsequent stages of said application of the brakes in accordance with manipulation of said brake valve device.

7. In a train control brake apparatus, in combination, a brake valve device manually operative 60 to control the application of the brakes, control mechanism automatically operative in accordance with traffic conditions to effect an application of the brakes, suppression means operative upon movement of said brake valve device to a 65 brake application position prior to automatic operation of said control mechanism for preventing such automatic operation thereof, and recapture means adapted to be operated after automatic operation of said control mechanism in effecting an application of the brake has begun, for permitting control of subsequent stages of said 70 brake application through the medium of said brake valve device.

8. In a train control brake apparatus, in combination, a brake valve device manually oper- 75

ative to control the application of the brakes, control mechanism automatically operative in accordance with traffic conditions to effect an application of the brakes, suppression means operative upon movement of said brake valve device 5 to a brake application position prior to automatic operation of said control mechanism for preventing said automatic operation thereof, and recapture means operative upon movement of said brake valve device to a brake application 10 position, after automatic operation of said control mechanism in effecting an application of the brakes has begun, for rendering said control mechanism ineffective to prevent manual control of subsequent stages of the brake application 15 through the medium of said brake valve device.

9. In a fluid pressure brake train control equipment, in combination, a brake valve device manually operative to effect an application of the brakes, automatic application valve 20 means having a normal position and operative to an application position in response to a change in signal indications for initiating a train control application of the brakes, means for retaining said automatic valve means in application 25 position and recapture means rendered effective by the operation of said brake valve device, after movement of said application valve means to application position and during retention thereof in said application position, for permitting further 30 control of the application of the brakes through the medium of the brake valve device.

10. In combination, a brake pipe, a discharge valve mechanism operable to effect a reduction in the pressure of fluid in said brake pipe to 35 effect an application of the brakes, train control apparatus automatically operative in response to a certain change in traffic signals to cause operation of said discharge valve mechanism to initiate a reduction in brake pipe pressure of a 40 certain degree, a manually movable member, and means operative upon movement of said member, during automatic operation of said train control apparatus, for effecting operation of said discharge valve mechanism to cause the reduction 45 in brake pipe pressure thereby begun to be limited to a different degree.

11. In a fluid pressure brake equipment, a brake pipe normally charged with fluid under pressure, train control apparatus automatically operative 50 in response to a change in traffic signals to initiate a reduction in brake pipe pressure of a certain degree, a manually operable member, recapture means adapted to be rendered effective upon movement of said member for limiting the degree 55 of reduction in brake pipe pressure effected by operation of said train control apparatus, and timing means for rendering said recapture means ineffective after a predetermined interval to prevent continued automatic reduction in the brake 60 pipe pressure to said certain degree.

12. In a fluid pressure brake, in combination, a brake pipe, a reduction in fluid pressure in which is adapted to effect an application of the brakes, train control mechanism automatically operative 65 in response to a signal indication to an application position for effecting a reduction in brake pipe pressure of a certain degree, brake valve means operable to control the application of the brakes, and recapture means rendered effective by operation of said brake valve means, following automatic operation of said train control mechanism to said application position, for temporarily limiting the amount of the reduction in brake pipe 70 75

pressure initiated by said train control mechanism and then permitting the reduction in brake pipe pressure to be continued to said certain degree.

13. In a fluid pressure brake, in combination, a 5
brake pipe, a reduction in pressure which effects an application of the brakes, train control mechanism automatically operative in response to signal indications to an application position for effecting a single-stage service reduction in brake 10
pipe pressure, manually controlled means operative to effect a service reduction in brake pipe pressure in one or more stages, and recapture means responsive to operation of said manually controlled means, following initial automatic operation of said train control mechanism to said application position, for so controlling the reduction in brake pipe pressure thus initiated as to split said reduction into two stages.

14. In a fluid pressure brake, in combination, a 20
brake pipe, a reduction in pressure which effects an application of the brakes, train control mechanism automatically operative in response to signal indications to an application position for effecting a single-stage service reduction in brake pipe 25
pressure, manually controlled means operative to effect a service reduction in brake pipe pressure in one or more stages, and recapture means responsive to operation of said manually controlled means, following initial operation of said train 30
control mechanism to said application position, said recapture means being operative for partially checking the reduction of brake pipe pressure thus initiated to permit control of further stages thereof through the medium of said manually controlled 35
means.

15. In a fluid pressure brake, in combination, a 40
brake pipe normally charged with fluid under pressure, train control mechanism automatically operative in response to signal indications to an 45
application position for effecting a single-stage service reduction in brake pipe pressure, an engineer's brake valve device movable to a first service position and to a second service position for normally effecting a two-stage service reduction in 50
brake pipe pressure, and recapture means operative upon movement of said brake valve device to first service position, following operation of said train control mechanism to said application position, for at least temporarily diminishing the rate 55
at which the service reduction in brake pipe pressure initiated by the train control mechanism is continued.

16. In a fluid pressure braking system for a railway train, in combination, a brake pipe normally 55
charged with fluid under pressure, an equalizing reservoir normally charged with fluid at brake pipe pressure, a discharge valve mechanism operative upon a reduction in the pressure of fluid in said equalizing reservoir to vent fluid under pressure from said brake pipe for effecting an application 60
of the brakes, a normally vented reduction limiting reservoir, a second normally vented reduction reservoir, train control apparatus automatically operative in response to an adverse 65
traffic signal to establish communication from said equalizing reservoir to both said reduction reservoirs, recapture valve means operative to cut off communication from said equalizing reservoir to said second reduction reservoir, and a brake valve 70
device movable to a brake application position for effecting operation of said recapture valve means, whereby the rate at which the brake pipe pressure is reduced by operation of said train control apparatus is controllable through the medium of said 75
brake valve device.

17. In a fluid pressure brake system for a railway train, in combination, a brake pipe normally charged with fluid under pressure, an equalizing reservoir normally charged with fluid at brake pipe pressure, a discharge valve mechanism operative upon a reduction in the pressure of fluid in said equalizing reservoir to vent fluid under pressure from said brake pipe for effecting an application of the brakes, a normally vented reduction limiting reservoir, a second normally vented reduction reservoir, train control apparatus automatically operative in response to an adverse traffic signal to establish communication from said equalizing reservoir to both said reduction reservoirs, a normally open valve operative to cut off the communication between said equalizing reservoir and said second reduction reservoir, a movable abutment subject to the pressure of fluid in a chamber for operating said valve, and a brake valve device movable to a brake application position for supplying fluid under pressure to said chamber.

18. In a fluid pressure braking system for a railway train, in combination, a brake pipe normally charged with fluid under pressure, an equalizing reservoir normally charged with fluid at brake pipe pressure, a discharge valve mechanism operative upon a reduction in pressure of fluid in said equalizing reservoir to vent fluid under pressure from said brake pipe to effect an application of the 30
brakes, train control apparatus automatically operative in response to an adverse traffic signal to vent fluid under pressure from said equalizing reservoir, recapture valve means operative to diminish the amount of fluid under pressure 35
vented from said equalizing reservoir by automatic operation of said train control apparatus, and a brake valve device movable to a brake application position for effecting operation of said recapture valve means, whereby the application of 40
the brake initiated by operation from said train control apparatus is controllable through the medium of said brake valve device.

19. In a fluid pressure braking system for a railway train, in combination, a brake pipe normally charged with fluid under pressure, an equalizing reservoir normally charged with fluid at brake pipe pressure, a discharge valve mechanism operative on a reduction in the pressure of fluid in said equalizing reservoir to vent fluid under pressure from the brake pipe for effecting an application of the brakes, a normally vented reduction limiting reservoir, a second normally vented reduction reservoir, train control apparatus automatically operative in response to an adverse traffic signal to establish communication from said equalizing reservoir to both said reduction reservoirs, a valve operative to control communication between said equalizing reservoir and said second reduction reservoir, a spring normally maintaining said valve open, a movable abutment operative upon an increase in pressure of fluid in a chamber for closing said valve, manually operable means for supplying fluid under pressure to said chamber, and a restricted atmospheric communication adapted to permit gradual escape of fluid under pressure thus supplied to said chamber, whereby after a predetermined interval said spring again becomes effective to open said valve.

20. In a fluid pressure brake system for a railway train, in combination, a brake pipe normally charged with fluid under pressure, an equalizing reservoir normally charged with fluid at brake pipe pressure, a discharge valve mechanism op- 75

erative on a reduction in the pressure of fluid in said equalizing reservoir to vent fluid under pressure from said brake pipe to effect an application of the brakes, a train control apparatus automatically operative in response to an adverse traffic signal to vent fluid under pressure from said equalizing reservoir, recapture valve means subject to and operative upon an increase in the pressure of fluid in a chamber for limiting the amount of fluid under pressure vented from the equalizing reservoir by automatic operation of said train control apparatus, a recapture reservoir, and manually operable brake valve means having one position for maintaining said recapture reservoir charged with fluid under pressure, and movable to a brake application position for supplying fluid under pressure from said recapture reservoir to said chamber, whereby when said train control apparatus is automatically set in operation the rate at which brake pipe pressure is reduced is controllable through the medium of said brake valve means.

21. In a train control brake system, in combination, an application valve mechanism automatically operative from a release position to an application position in response to an adverse signal indication for effecting an application of the brakes of a certain degree, a suppression valve device operative on an increase in fluid pressure in a chamber to prevent subsequent movement of said application valve mechanism to said application position, a recapture valve mechanism operative upon an increase in fluid pressure in another chamber to limit the degree of an automatic application of the brakes initiated by said application valve mechanism after movement thereof to said application position, and a brake valve device manually movable to a brake application position for supplying fluid under pressure to both said chambers.

22. In a train control brake system, in combination, an application valve mechanism automatically operative from a release position to an application position in response to an adverse signal indication for effecting an application of the brakes of a certain degree, a suppression valve device operative on an increase in fluid pressure in a chamber to prevent subsequent movement of said application valve mechanism to said application position, a recapture valve mechanism operative upon an increase in fluid pressure in another chamber to limit the degree of an automatic application of the brakes initiated by said application valve mechanism after movement thereof to said application position, a recapture reservoir adapted to be normally charged with fluid under pressure, and a brake valve device manually movable to a brake application position for supplying fluid under pressure from said recapture to both of said chambers.

23. In a train control brake system, in combination, a brake pipe, an application valve mechanism automatically operative from a release position to an application position in response to an adverse signal indication for venting fluid under pressure from said brake pipe at a certain rate for effecting application of the brakes, a suppression valve device operative upon an increase in fluid pressure in a chamber to prevent subsequent movement of said application valve mechanism to application position, a reservoir, and a brake valve device operative in a running position to maintain said reservoir charged with fluid under pressure, said brake valve device being operative when moved to a first service position to supply fluid

under pressure from said reservoir to said suppression valve chamber and when moved to a second service position to supply fluid under pressure from said brake pipe to said chamber.

24. In a fluid pressure brake, in combination, a brake pipe, a reduction in pressure in which is adapted to effect an application of the brakes, train control mechanism automatically operative in response to a change in a signal indication to effect a reduction in brake pipe pressure, recapture valve means operative to cause said reduction in brake pipe pressure to be effected in two stages after the reduction in brake pipe pressure has been initiated by operation of said train control mechanism, and means operable manually for effecting the operation of said valve means.

25. In a fluid pressure brake, in combination, a brake pipe, a reduction in fluid pressure in which is adapted to effect an application of the brakes, a normally charged equalizing reservoir, discharge valve mechanism operative in response to a reduction in fluid pressure in said equalizing reservoir to effect a corresponding reduction in fluid pressure in said brake pipe, a reduction reservoir volume, train control apparatus automatically operative in response to a change in a signal condition to vent fluid under pressure from said equalizing reservoir into said reduction reservoir volume, recapture means operative to reduce said reduction reservoir volume, and manually controlled means for effecting the operation of said recapture means.

26. In a fluid pressure brake train control equipment, in combination, a brake pipe, an equalizing reservoir, a discharge valve mechanism operative on a reduction in fluid pressure in said equalizing reservoir to vent fluid under pressure from said brake pipe, a brake valve device manually operable to vent fluid under pressure from said equalizing reservoir through one communication, brake application valve means having a normal position and automatically movable therefrom on a change in traffic signals to an application position for cutting off said communication and for establishing an additional communication through which fluid under pressure is vented from said equalizing reservoir, and recapture means responsive to manipulation of said brake valve device for limiting the venting of fluid under pressure through said additional communication.

27. In a fluid pressure brake train control equipment, in combination, a brake pipe, an equalizing reservoir, a discharge valve mechanism operative on a reduction in fluid pressure in said equalizing reservoir to vent fluid under pressure from said brake pipe, a brake valve device manually operable to vent fluid under pressure from said equalizing reservoir through one communication, brake application valve means having a normal position and automatically movable therefrom on a change in traffic signals to an application position for cutting off said communication and for establishing an additional communication through which fluid under pressure is vented from said equalizing reservoir, and recapture means operative to control the flow of fluid under pressure from the brake pipe through said additional communication in accordance with manual operation of said brake valve device.

28. In a fluid pressure brake system for a railway train, in combination, a brake pipe normally charged with fluid under pressure, a brake valve device normally adapted for operation to effect a reduction in brake pipe pressure of any

- desired degree, train control mechanism automatically operative, in response to communication of an adverse traffic signal, to initiate a predetermined degree of reduction in brake pipe pressure 5 and to render said brake valve device ineffective for said normal operation, and recapture means operative in response to manipulation of said brake valve device to control further stages of a reduction in brake pipe pressure as effected by 10 continued operation of said train control mechanism.
29. In an automatic train control brake equipment for a railway train, in combination, a brake pipe normally charged with fluid under pressure, 15 a brake valve device normally adapted for operation to effect a reduction in brake pipe pressure of any desired degree, train control mechanism automatically operative, in response to communication of an adverse traffic condition, to initiate 20 a predetermined degree of reduction in brake pipe pressure and to render said brake valve device ineffective for said normal operation, and recapture means operative in response to manipulation of said brake valve device, after automatic operation 25 of the train control mechanism has begun, to control the rate at which the reduction in brake pipe pressure is effected by operation of said train control mechanism.
30. In an automatic train control brake system, 30 in combination, a brake pipe normally charged with fluid under pressure, an equalizing reservoir normally charged with fluid under pressure, an equalizing piston subject to the opposing pressures of fluid in the brake pipe and in said 35 equalizing reservoir, a normally closed discharge valve operative by said piston to vent fluid under pressure from the brake pipe in accordance with reduction in equalizing reservoir pressure, a train control application valve mechanism automatically operative in response to an 40 adverse traffic signal to vent fluid from said equalizing reservoir for causing a service application of the brakes, and a normally closed maintaining valve operative by said equalizing piston to supply fluid under pressure to the brake pipe 45

in the event of reduction of pressure in said brake pipe below that in said equalizing reservoir, whereby the train control reduction in brake pipe pressure is prevented from exceeding the desired rate. 5

31. In a fluid pressure brake and train control system, in combination a brake pipe, an equalizing reservoir, an equalizing discharge valve mechanism operative upon a reduction in pressure in the equalizing reservoir for venting fluid under pressure from the brake pipe, a reduction reservoir, an application valve device operative in response to an adverse signal indication for establishing communication from the equalizing reservoir to the reduction reservoir, a recapture valve device for controlling communication from the equalizing reservoir to the reduction reservoir, and a manually operable valve device for controlling the operation of said recapture valve device. 10 15

32. In an automatic fluid pressure brake and train control equipment of the class involving a brake pipe, a brake valve device normally operable by manual control to effect reduction of the pressure of fluid in said brake pipe in any number 20 of stages for effecting a brake application of a desired degree, and train control mechanism automatically operative, in response to communication of an adverse traffic signal, to take over control of said brake valve device for initiating a predetermined degree of reduction in brake pipe pressure in a single stage while rendering said brake valve device ineffective for said normal operation, in combination, a recapture valve adapted for cooperation with said train control mechanism to prevent an automatically initiated train control reduction in brake pipe pressure from exceeding a desired rate, and fluid pressure responsive means controlled by manipulation of said brake valve device to actuate said recapture valve, whereby the engineer may regain at least partial control of an automatic application of the brakes being effected through the medium of the train control mechanism. 25 30 35 40
